CAP OR SIMILAR ARTICLE

Herman B. Lermer, 3 Cherrywood Circle,
West Orange, N.J.

Filed Dec. 2, 1963, Ser. No. 77,642

Term of patent 14 years

(Cl. D58—26)

Fig. 1

Fig. 2

Fig. 3

Fig. 4

Fig. 5

FIGURE 1 is a side perspective view of a cap or similar article embodying my new design.

FIGURE 2 is a left side elevational view thereof.

FIGURE 3 is a front elevational view thereof.

FIGURE 4 is a top plan view thereof.

FIGURE 5 is a bottom plan view thereof.

The dominant feature of my design lies in the provision of a generally planar suspension member being bounded by a pair of oppositely disposed serpentine curves, the outer ends of which are spaced a short distance apart from each other, there being an elongated slot extending into the body of said suspension member between said serpentine curves and leading to a generally circular recess disposed between said serpentine curves, all as shown.

I claim:

The ornamental design for a cap or similar article, substantially as shown and described.
